STOP MOTION

Eugene St. Pierre, Pawtucket, and Joseph Wawzonek, Central Falls, R. I., assignors to Hemphill Company, Pawtucket, R. I., a corporation of Massachusetts

Application January 31, 1952, Serial No. 269,216

3 Claims. (Cl. 66—163)

1

This invention relates to circular, independent needle, knitting machines of the dial and cylinder type; and, particularly, to stop motions for preventing needle damage and yarn load-ups in such machines.

The primary object of the invention is to provide a stop motion system which will be absolutely reliable, but less expensive and less complicated than those of the prior art. A further object is to insure that the stop motion system will provide for a "safe failure"; i. e., will render the knitting machine inoperative if there is any electrical failure in the stop motion system, thereby avoiding the risk of reliance upon a device which might actually be inoperative.

The above and other related objects are accomplished in accordance with the invention by a stop motion system which includes: a single mechanical trigger for protecting both the dial and the cylinder needles, mechanical means for withdrawing the trigger from the vicinity of the needles to render it inoperative when it might interfere with their operation, an electrical switch actuated by the trigger and controlling current to a solenoid which actuates the belt shipper or other means for stopping the rotation of the dial and cylinder.

The operation of the invention is explained by reference to the accompanying drawing, wherein:

Figure 1 is a diagrammatic view of a stop motion system after the manner of the invention, showing the mechanical trigger in its "locked" position; i. e., permitting the machine to operate;

Figure 2 is a plan view from below of the mounting for the mechanical trigger of Figure 1;

Figure 3 is a plan view of the mounting and trigger of Figure 1, with the trigger in "unlocked" or released position, i. e. causing the machine to stop;

Figure 4 is a diagrammatic side view of the mounting and trigger of the other figures, showing the location of the trigger with respect to dial and cylinder needles when in the "locked" position of Figure 1.

As shown in Figure 1, this stop motion system includes a mechanical trigger 1 supported upon a retractable mounting 2 and actuating an electrical switch 3 which controls current to a solenoid 4. The solenoid, in turn, is connected to a lever 5 which controls the mechanism by which driving the cylinder and the dial is effected in a manner familiar to the art and not shown or discussed here.

The trigger 1 is disposed substantially in a

2

plane extending from approximately the intersection of the longitudinal axes of said dial and said cylinder needles and is mounted on the machine in such a manner that, when it is thrust forward, as shown in Figure 1, so that spring 6 is compressed and its end 7 is locked against stud 8, its tip 9 is interjected into the space between the hooks of the dial and needle cylinders (10 and 11, respectively) in their normal positions, as shown in Figure 4.

In the locked position, the surface 12 of the trigger is pressed against the actuator 13 of the switch 3, thereby closing the switch and permitting electrical current from the transformer 14 to cause the solenoid 4 to hold the lever 5 in position to permit the machine to be driven by its associated driving mechanism.

If the butt of either a cylinder needle 11 or a dial needle 10 should break and, as a consequence, the needle is not withdrawn at the proper time, it will strike the tip 9 of the trigger 1 as the machine rotates, thereby dislodging its end 7 from the stud 8 and causing the spring 6 to force the trigger backward upon the mounting 2. This releases the surface 12 from the actuator 13, as shown in Figure 3, opens the switch 3, and breaks the electric current to the solenoid 4. The de-energized solenoid allows the spring 23 to pull the lever 5 out of its engaged position, thereby disconnecting the driving mechanism of the machine.

A similar release of the trigger 1 will take place when there is a "load-up" of yarn on either dial or cylinder needles.

The fact that the spring 6 removes the trigger 1 from its proximity to the needles once the tip 9 has been struck prevents the trigger from becoming bent or damaged by any further rotation of the needles before the stopping action takes effect.

At certain times during the operation of the machine, the cylinder needles are raised high enough to hit against the trigger in its normal operating position, e. g. during reciprocatory knitting of the heel and toe. At such times, it is necessary to withdraw the trigger 1 without, at the same time, releasing the actuator 13 of the switch 3. This is accomplished by making the trigger mounting 2 retractable so that the entire assembly can be withdrawn away from the needles to the position designated by the dotted lines in Figs. 1 and 2.

The means for accomplishing this retraction is a lever 15 bearing against a stud 16 underneath the mounting plate 2, as shown in Fig. 2. The

mounting 2 is slidably held on a bracket 17 by means of a slot 18 and guiding screws 19 and 20.

The bracket 17 is mounted upon the pivoted carrier ring (not shown) which supports the entire dial unit (also not shown) in conventional manner. This method of supporting the trigger assembly permits it and its associated retracting mechanism to be withdrawn from the cylinder area for purposes of repair, independent operation of the cylinder, etc.

Normally, a spring 21 fastened between the mounting 2 and the forward end of the bracket 17 holds the mounting in its forward position, as shown in Fig. 1.

A rod 22 connected to the pattern drum (not shown) pulls the lever 15 against the stud 16, as shown in Fig. 2, and thereby removes the entire assembly, including the trigger, from proximity to the needles when desired without breaking contact at the switch 3.

In case there should be a failure of electrical current to the transformer 14, the solenoid 4 would be immediately de-energized, thereby releasing the lever 5 and stopping the machine. This ensures that the operator will not rely upon the stop motion to prevent needle smashes or load-up of fabric when the system has suffered an electrical failure.

Another feature of this stop motion is its closed electrical system as distinguished from a grounded system, i. e., it is not electrically connected to the chassis of the machine. This reduces the possibility of electrical shocks to operating personnel from short circuits, etc.

In this manner, the invention provides an inexpensive, efficient, and safe stop motion system for circular knitting machines of the dial and cylinder type.

What is claimed is:

1. In a circular, independent needle knitting machine having dial and cylinder needles disposed at substantially right angles to each other and means for stopping the machine a stop motion system which includes a mechanical trigger disposed in a plane extending from approximately the intersection of the longitudinal axes of said dial and cylinder needles, a mounting for said trigger retractable in said plane in a direction away from said needles, said trigger being automatically retractable upon said mounting when struck by said needles or yarn carried by them, a solenoid adapted to operate said means for stopping said machine, and means for providing an electrical current to said solenoid including a switch actuated by said trigger.
2. The invention according to claim 1 and wherein said trigger is adapted to actuate said switch regardless of whether said mounting is in retracted or unretracted position.
3. A stop motion system according to claim 1 and wherein said electric current is at no time during the operation of said system grounded to said machine.

EUGENE ST. PIERRE,
JOSEPH WAWZONEK.
